UNITED STATES PATENT OFFICE.

JOHN W. DARLEY, JR., OF BALTIMORE, MARYLAND, ASSIGNOR TO THE UNIVERSAL STEEL PACKAGE CO., A CORPORATION OF DELAWARE.

METALLIC BARREL.

1,240,030.

Specification of Letters Patent. Patented Sept. 11, 1917.

Application filed October 21, 1915. Serial No. 57,190.

To all whom it may concern:

Be it known that I, JOHN W. DARLEY, Jr., a citizen of the United States, residing at Baltimore, in the State of Maryland, have 5 invented certain new and useful Improvements in Metallic Barrels; and I do hereby declare the following to be a full, clear, and exact description of the invention, such as will enable others skilled in the art to which 10 it appertains to make and use the same.

My invention relates to metallic barrels, and the object of my invention is to produce a metal barrel, which shall be light, strong, of a bilged form and which shall be so constructed that the head can be readily removed where access to the interior is desired.

A further object of my invention is to provide a barrel which can be readily knocked down when the barrel is to be 20 re-shipped for re-use as a container.

This present application for United States Letters Patent relates only to the construction of the head and chine ring and means by which the head is secured to the staves 25 of the barrel.

Another application for United States Letters Patent Serial No. 57,189 is filed herewith showing the construction of the staves and hoops.

30 In the drawings—

Figure 1, is a perspective view of my improved barrel;

Fig. 2, is a partial longitudinal section of the barrel along the line 2—2 as shown in 35 Fig. 1;

Fig. 3, is a perspective view of one stave of my improved barrel;

Fig. 4, is a perspective view of the head of my improved barrel;

40 Fig. 5 is a perspective view of the chine ring for my improved barrel;

Fig. 6, is a top plan view of the juncture of two staves and it also shows the position of the head with reference to the staves 45 when the head is first introduced within the staves; and

Fig. 7, shows the relation between the head and one stave after the head has been moved into the locking position.

50 In the drawings 10 represents a stave which may be corrugated or in any wise strengthened.

The staves are provided with ribs 17 and 18 along their edges and they may be 55 secured together in any approved manner

and are to be retained in place by hoops such as 11—11.

The staves are provided at the ends with portions such as 12—12, which when the staves are assembled together form a substantially cylindrical flange on the edge of the barrel.

Each portion 12 of each stave is provided with a U shaped flange 13 near the center thereof for a purpose hereinafter specified.

Each portion 12 is further provided with tabs 14 adjacent to the flange 13, and with side extensions 15 and 16. The side extension 16 of one stave is adapted to lap over the side extension 15 of the adjacent stave 70 (as shown in Fig. 6) when the rib 18 of the former stave is introduced between the side extensions 15 of the latter stave in order to secure the rib 18 of the former stave to the rib 17 of the latter stave.

After the staves are joined together as just described the hoops, 11—11 are driven over the body of the barrel to secure same together.

My improved head compromises a cruciform strengthening rib 19 having depressions such as 20 between the arms thereof and a strengthening bead 21 joining the ends of the said arm. Near the ends of the arms 22 and on both sides of each arm flat places 85 such as 22^a are provided. A flat annulus 23 extends outwardly from the head 21 and is provided on its exterior with a flange 24.

The flange 24 is slit at its upper portion so as to provide a plurality of portions such 90 as 25 equal in number to the number of staves in the barrel. Between the portions 25 the portions 26 are bent inwardly for a purpose hereinafter described.

For the purpose of strengthening the chine 95 of the barrel, I provide the chine ring 30, (shown in Fig. 5), which is substantially U shaped in cross section and is provided with a flange 27 forming an obtuse angle with the inner side thereof. The top of the 100 chine ring is provided with a plurality of holes such as 31 equal in number to the number of staves in the barrel. One end of the strip of metal of which the chine ring is composed is provided with two tabs 28—28, 105 and the other end of said strip is provided with two holes 29—29 for the reception of said tabs. The end of the strip provided with the holes 29—29 is enlarged so as to pass over the end of the strip provided with 110

the tabs 28—28 so that said tabs may be made to register with the holes 29—29. One of the tabs 28 is bent outwardly through the outside hole 29 and the other tab is bent inwardly through the inside hole 29 and then both tabs are bent backwardly (as shown in Fig. 1,) with reference to the inside tab, in order to lock the ends of the strip together.

10 The operation of assembling my improved barrel is as follows:—

After the staves 10 have been assembled and bound in place by hoops 11—11, the head shown in Fig. 4 is to be introduced 15 within the approximate cylinder formed by the portions 12 on the ends of the staves, in such a manner that the portions 25 of the flange 24 of the head will pass downwardly between the ends of two adjacent portions 20 13—13 on the staves. The portions 13—13 are of such a circumferential length so as to allow approximately one-fourth of an inch space between the abutting ends of two adjacent portions 13—13 and the interdisposed 25 portions 25 of the head flange 24. The head is then pushed downwardly until the annular portion 23 thereof rests upon the ends of the ribs 17 and 18 on the staves. The head is then to be given a twist in order to 30 bring the portions 25 on the head flange 24 under the flanges 13 on the ends of the staves thus locking the head with the staves. In order to prevent the flanges from bending outwardly and releasing the portions 25 when subjected to heavy stresses acting from the inside of the barrel outwardly, the bent portions 26 are provided which overlie the ends of the flanges 13, then in order to secure

the bent portions 26 from releasing the ends of the flanges 13, the inside of the U shaped 40 chine ring is made of such dimensions that when driven down it will clamp the portions 26 against the flanges 13 and the latter against the portions 25 of the head flange 24, thus effectually securing the head in place 45 and preventing any shifting of the head with reference to the staves under heavy stress.

In order to provide for the ready placing of the chine ring 30 in position, the beveled 50 portion 27 is provided to press the portions 26 toward the flanges 13. When the chine ring is in position, the tabs 14 pass through the holes 31 and are bent over inwardly (as shown in Figs. 1 and 2) in order to retain 55 the chine ring in place.

I claim:—

1. The combination with a plurality of staves each having flanges on a portion of the ends thereof, of a head provided with a flange having portions adapted to be passed under said flanges on said staves to lock said head and staves together, said flange on said head also having portions adapted to pass over the ends of the flanges on said staves. 60

2. The combination with a plurality of staves each having flanges on the ends thereof, of a head having a flange resting under the flanges on said staves, a chine ring substantially U shaped in cross section having 70 holes in the top thereof and fitting over said staves and the flange on said head, and tabs on said staves passed through said holes and bent to retain said chine ring in place.

In testimony whereof, I affix my signature. 75
JOHN W. DARLEY, JR.
